FOLDABLE POCKET KIT FOR ACCESSORIES

Charles G. Davis, San Leandro, Calif.

Application March 14, 1951, Serial No. 215,557

4 Claims. (Cl. 150—52)

1

This invention relates to foldable wallets or kits having stepped pocket openings, and more particularly relates to such kits in which overlying pockets are provided of transparent or translucent material.

Such wallets, especially when having accessories therein, are generally referred to as kits, and therefore are referred to herein in such manner. They are essential equipment to members of the Armed Forces, and valuable to other travelers, for carrying upon the person in convenient and readily available form such things as identification cards, small photographs, sewing and mending accessories, such as needles, scissors, thread, buttons, small toilet articles, and the like.

The invention comprises a kit of elongated flexible backing cover strip of foldable sections which, when folded, may be securely closed by the usual snap-fastener button, the backing cover strip having aligned longitudinally of its inner face a plurality of pocket sections in which opposite end sections are shorter than a central section, the length of the central pocket section defining the length of the folded kit, the pockets being closed at one longitudinal edge and open at the opposite edge in spaced parallel relation to the adjacent longitudinal edge of the back cover strip. Preferably there are two rows of relatively overlying pockets which have their openings relatively stepped to provide facility of access, and in which a flexible textile flap is provided adjacent to the open edge of the pockets and removably overlying the openings thereof, the material of the pockets being preferably of transparent or translucent material. The rows of pockets are spaced from one end of the cover strip, providing an end flap of sufficient length to fold over and enclose both planar faces of the central section when the kit is folded, and having the button fastener thereon for securing them in closed position.

An object of the invention is to provide a rugged economical and simplified kit container of compact structure which may be carried flat in a normal pocket of a suit or garment of the wearer, and to provide in the kit separate pockets readily accessible yet closable against inadvertent loss of the enclosed contents.

Another object is to provide a flexible kit of convenient flat form having pockets in which the contents of the pockets are visible and which access to pockets is facilitated by relatively stepping the opening of the pockets therein.

A preferred form in which the invention may

2

be embodied is more fully set forth in the one example of structure described herein and as illustrated in the accompanying drawing and defined by the appended claims.

In the drawing:

Fig. 1 is a plan view of the invention, in unfolded position.

Fig. 2 is a section of line 2—2 of Fig. 1.

Fig. 3 is an enlarged fragmentary view of a portion of Fig. 2.

Fig. 4 is a perspective of the invention, in folded position.

Fig. 5 is a fragmentary, partially broken away view of a portion of Fig. 1.

Referring to the drawing in which like reference characters indicate corresponding parts in the several views, 10 indicates an elongated backing cover strip of tough, foldable, flexible, wear-resisting material, which is preferably also resistant to penetration by moisture, and of sufficient length and width to provide for a plurality of aligned pockets, and a foldable end flap.

The outer face of the cover strip may be designated 11 and the inner face 12. Mounted longitudinally of the inner face 12 of the cover strip 10 and aligned therewith, are a plurality of pockets of which there are preferably two rows of the pocket sections, one row overlying the other, and each row having three pocket sections aligned longitudinally of the strip, as indicated 13a, 13b, 13c, and 14a, 14b and 14c, in the respective rows. The center pocket sections are longer than the pocket sections at the opposite ends thereof and said end pockets preferably are of substantially equal length relative to each other. One end of these rows of pockets is spaced from an end of the back cover sheet 10, providing an end flap 12a, the pockets preferably extending in alignment from the end flap substantially to the opposite end of the cover strip as at 12b, so that the pocket strips and the said opposite end of the cover strip are coterminous with the adjacent end of the back cover strip, whereby a narrow transverse strip 10a of the adjacent end of the back cover strip may be folded over the adjacent ends of the pocket strips and included in a single stitched seam at said terminal end as at 15, the opposite end of the strip of pocket sections being closed and connected to the cover strip by transverse stitching 15b. Intermediate the length of the strip of pockets are relatively spaced lines of transverse stitching 15a which also connect the pocket strips with the cover strip and define the length of the central pockets 13b and 14b, said stitching

50

55

15a also providing readily bendable transverse lines at the ends of the central pocket which serve as fold lines of the pocket strip, thus providing overlying relatively long central pocket sections 13b, 14b, and relatively shorter pocket sections at the opposite ends thereof indicated 13a, 14a and 13c and 14c, the end pockets being preferably of substantially equal length relatively.

One longitudinal edge of the pockets is closed and secured to the cover strip by a longitudinal line of stitching 16, and the opposite edge of each of the pockets has an opening indicated 17 and 18 in the respective rows, which openings are spaced from and parallel to the opposite edge of the cover strip, the pocket edges of the openings 17 and 18 being in stepped relation to facilitate access to the contents of the several overlying pockets. The edges of each of the rows of pockets at the opening thereof have longitudinal reinforcing seams 19 the pocket material being integrally folded upon itself and stitched at 20. Preferably the pockets are of flexible transparent material, or at least sufficiently translucent material so that contents of the pockets may be visible through the sheets of pocket material. Such material is readily available as a standard commercial plastic product.

The overlying pockets are preferably formed of an integral sheet of material longitudinally folded upon itself at the closed longitudinal edge of the pockets, the fold being offset from the center of the sheet whereby the edges of the openings of the pockets are relatively offset or stepped, and providing a closed edge which is included within the stitching 16 to the back cover sheet.

Each of the opposite longitudinal edges of the back cover strip 10 is provided along its entire length with a binder strip 21 and 22, which may conveniently be of the same type of material of which the pockets are formed. In order to avoid exposed sharp tearable edges of the material in these binder strips 21 and 22, either on the inside or outside of the kit, the strip material is retroverted inwardly upon itself at each of its opposite longitudinal edges sufficiently to form parallel edge fold 23, and leave the central portion of the strip free of such folds. The central portion of the edging strips is bent on its longitudinal axis to provide a strip substantially U-shaped in transverse section which are mounted upon and enclose the opposite longitudinal edges of the back cover sheet 10 and overlying members at said edges, the stitching 16 being employed for the purpose at the bottom or closed edge of the pockets and the stitching 24 binding the edging strip at the opposite edge of the cover sheet.

At the edge of the back cover adjacent the openings of the pockets the binder strip 22 encloses one edge of a flexible penetrable textile strip of cloth 25 which is preferably of the same length as the rows of pockets, the stitching 24 securing said edge within the binder strip. The width of the strip of cloth is sufficient to overlap the openings of the pockets and overlie a substantial portion of the pocket bodies, thus providing a closure flap for the openings of the pockets and also affording a padding for preventing faces of the pockets from chafing upon each other when the kit is folded. Obviously, the penetrability of the strip 25 permits it to be used for inserting therein needles, safety pins, jewelry pins and the like.

It is to be understood that the stitchings 16 and 24 extend the entire length of the binder strips 21 and 22, the stitching 16 simultaneously sewing within the folds of the binder strip 21 the closed bottom longitudinal retroverted edge of the pocket strips, and the stitching 24 including one edge of the textile cover flap 25.

Since the pocket sections at the opposite ends of the pocket strips, that is, pockets 13a, 14a and 13c, 14c, are of substantially the same length and are shorter in length than the central pocket sections 13b and 14b, the length of the central pocket sections define the length of the kit when the kit is folded into form as shown in Fig. 4. Therefore, when the shorter end pocket sections are folded at stitching lines 15a to overlie the longer central pocket sections 13b, 14b, the end pocket sections do not extend the full length of the center sections 13b, 14b, and thereby the thickness of one layer of the pockets is eliminated at each of the fold lines 15a when the kit is folded, thus avoiding bulging at the folds if the pockets have a substantial quantity of contents therein. This arrangement of fold lines at opposite ends of a longer central section, and the provision of shorter pocket sections at the opposite ends thereof, makes a fold line 15c occur at the longitudinal central portion of the end flap 12a whereby the end flap 12a will fold around and enclose an end portion of both opposite planar faces of the folded kit and will fold around one end of the folded kit at the fold line 15c. But since the end flap 12a is free of any overlying pocket sections, the thickness of the folded kit is not substantially increased or bulged by the fold at the line 15c.

Suitable means are provided for releasably locking the kit shut in folded form, and conveniently may be exemplified by conventional snap fasteners, the button being 26 intermediate the ends of the outer face 11 of the cover strip and the recessed snap member 27, being adjacent the end edge of the foldable end portion 12a.

45 While in the present instance three pockets are illustrated in each of the overlying rows, a single row of pockets may be employed if desired, or more or less pockets may be placed in each row. For example, the row of pockets 14a, 14b, 14c may be stitched transversely at 15a to preserve the 50 fold lines, and the row of pockets 13a, 13b, 13c may have the transverse stitching eliminated intermediate its ends to provide a single elongated pocket in which the usual elongated paper money may be carried in foldable flat form.

55 What I claim as new and patentable is:

1. A foldable accessory kit comprising an elongated foldable flexible back cover strip, a row of three aligned flexible pocket sections mounted on the inner face of the cover strip, the central section having fold lines at its opposite ends defining the length of the kit when folded, the pocket sections at the opposite ends of the central section being shorter in length than the central pocket section, the row of pocket sections being substantially coterminous with the cover strip at one end and having the opposite end thereof spaced from an adjacent end of the cover strip providing an end flap aligned with the pocket sections, said end flap having a fastener thereon and being free of overlying pocket sections, the pockets having a bottom closure connected at one longitudinal edge of the back cover strip and the openings of the pockets being adjacently spaced from and parallel with the opposite longitudinal edge of the cover strip, a flexible pen-

trable textile flap connected to the inner face of the back cover strip at said opposite edge of the cover strip, said flexible penetrable flap being of a length substantially the same as the row of pockets and of a width sufficient to overlap the openings of the pockets, and snap fastener means mounted on the outer face of the cover strip for releasable engagement by the fastener on the end flap for securing the strip at a folded position when the end pocket sections are folded to overlie the central section, the said end flap being of a length extending beyond the adjacent end pocket sufficiently to provide a portion which overlies the opposite planar faces of the center pocket when the kit is folded and said fasteners are interengaged whereby a fold line of the folded kit is intermediate the ends of said end flap.

2. A device of the character described having the elements of claim 1 and in which the central pocket section is of lesser transverse width than its length parallel to the elongated longitudinal edges of the cover strip and in which a binder strip encloses the opposite longitudinal edges of the back cover strip and the respective edges of the flexible textile flap and pockets which are connected therealong.

3. A device of the character described, having the elements of claim 1 and in which the central pocket is continuous between the fold lines at its opposite ends, and the pockets are of transparent material, and a stitched binder strip of U-shaped cross sections encloses each opposite longitudinal edge of the back cover strip and the respective edges of the flexible textile flap and pockets connected therealong, said binder strip having its opposite edges retroverted inwardly upon itself.

4. A foldable accessory kit comprising an elongated foldable flexible back cover strip, a plurality of relatively overlying longitudinal rows of flexible pockets overlying the inner face of the cover strip and secured thereto at one longitudinal edge of said cover strip whereby the bottoms of the pockets are closed and the openings of the pockets are parallel to the opposite longitudinal edge of the cover strip, said pocket openings being relatively stepped and spaced from said opposite longitudinal edge, each row having

a central pocket section and opposite end pocket sections, the end sections being shorter in length than the central pocket section, the opposite ends of the overlying central sections being secured to the back cover sheet by transverse stitching providing fold lines for the overlying rows of pockets of the kit, the rows of pockets being spaced from one end of the cover strip providing a flexible end flap longitudinally aligned with the pockets, a fastener member mounted on said end flap, said overlying rows of pockets being integral sheet material folded upon itself in overlying relation, the integral fold being secured to the back cover strip at the bottom closure of the pockets, and the openings of said rows of pockets being adjacently spaced in relatively stepped relation from the opposite edge of the back cover strip, the edges of the pockets at the openings thereof having an integral reinforced strip folded and secured upon itself, a flexible textile flap connected to said opposite edge of the back cover strip, said flexible textile flap being of a length substantially equal to the length of the rows of pockets and of a width sufficient to overlap the openings of the pockets, and fastener means on the cover strip engageable by the fastener member on the end flap for releasably securing the pocket sections and the cover strip in overlying folded relation, the end flap being of sufficient length whereby it may have a fold line intermediate its ends and may pass around one end of the folded kit and enclose an end portion of both opposite planar faces of the folded kit.
